METAL RECTIFIER

Edward Arthur Richards, London, England, assignor, by mesne assignments, to International Standard Electric Corporation, New York, N. Y., a corporation of Delaware

Application June 15, 1944, Serial No. 540,375
In Great Britain July 15, 1943

4 Claims. (Cl. 175—366)

1

This invention relates to improvements in metal rectifiers of the disc or plate type, for example the well known selenium disc type of rectifier, and has for one of its objects to provide an improved construction or assembly of such rectifiers.

Metal rectifiers of the disc or plate type are usually assembled by threading the discs and suitable spacing washers on an insulated spindle with threaded ends and securing the whole unit by nuts at each end of the spindle. Excessive pressure produced by over-tightening the nuts may cause damage to a disc or discs and it is particularly important to avoid this when a large number of individual discs is connected in parallel, since a breakdown in one disc may short-circuit the whole assembly. Under these conditions very heavy currents may flow and cause damage to the other arms of the rectifier.

According to a feature of the present invention the spindle is replaced by a spring which is designed so that the predetermined pressure which it exerts on the discs when assembled is sufficient to provide good electrical contact but not great enough to cause damage to the discs.

The above and other features of the invention will be better understood by reference to the accompanying drawings in which:

Fig. 1 is a front elevation of a rectifier element and associated bus-bars forming part of a large rectifier intended for the supply of heavy currents.

Fig. 2 is a plan thereof.

Fig. 3 is a central sectional elevation of the element shown in Fig. 1.

Fig. 4 is a central sectional elevation of a modified form of rectifier assembly incorporating the invention; and

Fig. 5 is an end elevation thereof.

Figs. 1-3 show, by way of example, a portion of a rectifier intended for the supply of heavy currents at low voltage which might be used as the power supply for electrolytic processes. Rectifier discs AA are assembled in pairs on a bar or plate B which may carry a number of pairs similar to those shown. The rectifier discs may be of the type in which a metal base plate is coated on one side with a layer of selenium to which, after suitable heat treatment, a counter-electrode of metal alloy is applied. Preferably, they are also of the so-called centre-contact type in accordance with U. S. Patent No. 2,314,104.

The discs are mounted with the base plates adjacent to the bar B so that when the counter-electrodes are connected together the two discs

2

forming a pair are electrically in parallel. The other pairs are connected in the same way so that the bar B forms a common terminal for all the discs which are mounted upon it.

5 Connection is made to the counter-electrode surface by the shaped washers CC and the current is conducted to these washers by thin metal strips D. These strips are formed with a constriction at E so that they act as a fuse in case a disc should develop a short-circuit in service.

A collar F through which a pin G is inserted and secured at each end anchors one end of the spring H. In assembling a pair of discs an insulating tube K is inserted in the hole in the bar 15 B and a disc A, washer C, connecting strip D and collar F are slipped on the tube on one side of the bar in the order stated. A disc A, washer C, connecting strip D and washer J are then placed on the tube on the opposite side of the bar.

20 The hook L of the spring then projects through the tube so that it can be engaged by a suitable tool in order to extend the spring and allow the pin M to be inserted to complete the assembly. This pin is cranked as shown to centralize the 25 spring and prevent the pin from working out owing to vibration. The outer ends of the connection strips D are secured by, and make contact with, a bolt N and bus-bar N¹ which is insulated from the bar B and serves as the common 30 connection to the counter-electrode surfaces of the discs.

It will be seen that the pressure exerted on the contact area of the discs is limited by the design of the spring and the thickness of the 35 various members and cannot exceed the value predetermined by these factors.

If desired, two or more discs may be assembled in series on either side of the bar without affecting the principle of the arrangement. A 40 longer tube and spring would, of course, be necessary to allow for the thickness of the additional discs and spacing washers.

Figs. 4 and 5, for example, show the application of the invention to the more conventional 45 type of rectifier assembly comprising a number of rectifier discs assembled in series. In this case the rectifier discs A are assembled on the insulating tube K together with the usual spacing washers O connecting tags P and insulating 50 washers Q at the ends, and electrical contact between the members is maintained by the tension of the spring H acting through the end collars F and J.

What is claimed is:

55 1. A metal rectifier assembly comprising a

plurality of parallel connected rectifier units assembled on a metal bar, each of said units comprising at least a pair of rectifier discs with their base plates adjacent said bar and electrically connected therewith, washers contacting the counter electrode surfaces of said discs, fusible metal connections associated with said washers and arranged to connect a plurality of said counter electrode surfaces in parallel, said discs, washers and fusible metal connections being assembled on the metal bar and maintained in electrical contact by means of a helical spring passing through an aperture in said bar.

2. A metal rectifier assembly as set forth in claim 1, in which said discs and said contact washers are threaded on a tube of insulating material and said spring extends through said tube and is anchored at its ends to cross members engaging thrust collars for transmitting the spring pressure to said contact washers and said discs. 15

3. A metal rectifier assembly as set forth in claim 1, in which said discs and said contact washers are threaded on a tube of insulating material and said spring extends through said tube and is anchored at its ends to cross members engaging thrust collars for transmitting the spring pressure to said contact washers and said discs, said cross members comprising diametrically arranged pins, one of which is coupled to one end of said spring and secured in a thrust collar, whereas the other pin is cranked to be self centering on the other thrust collar when the said spring is tensioned. 20 25 30

4. In a dry disc rectifier unit of the type that comprises a plurality of disc rectifier elements and spacer members assembled under tension in stacked coaxial relationship upon mounting means extending through centrally located openings in the disc elements and spacer members, the improved means for maintaining said elements under predetermined uniform constant tension that comprises a helical spring positioned within an axially extending opening in said mounting means and caps connected to the opposite ends of the spring cooperating with the terminal rectifier elements whereby said elements are spring-urged toward each other.
